VELOCIPEDE

James H. Byrn and Herbert E. Rolfe, Jr., Garden City,
and George Houtz, Northville, Mich., assignors to
Evans Products Company, Plymouth, Mich., a corpora-
tion of Delaware

Filed Dec. 30, 1960, Ser. No. 63,402

Term of patent 14 years

(Cl. D34—15)

FIGURE 1 is a front elevational view of a velocipede showing our new design;

FIGURE 2 is a rear elevational view thereof;

FIGURE 3 is a perspective view thereof on a reduced scale;

FIGURE 4 is a top plan view thereof on an enlarged scale; and,

FIGURE 5 is a side elevational view thereof as shown in FIGURE 4.

The dominant features of our design reside in the portions shown in full lines.

We claim:

The ornamental design for a velocipede, as shown and described.
